CLEANOUT PLUG

Wilbur H. Armacost, Scarsdale, N. Y., assignor to
The Superheater Company, New York, N. Y.

Application June 20, 1942, Serial No. 447,863

5 Claims. (Cl. 138—95)

The present invention relates to heat transfer apparatus and particularly to an improved cleanout plug for tubular fluid circulating elements.

Where, as in economizers, heat transfer tubes are positioned in parallel relation and interconnected for series fluid flow by return bends, it is desirable that access may be had to the interior of the tubes for cleaning them. Various types of removable closures have been provided at the return bends for this purpose; the present invention relates to a cleanout plug in which the closure element and the parts that maintain it in place within the return bend are removable as a unit so that they may be kept together to avoid loss and assure ready replacement. A further feature of the improved cleanout plug is that it is so constructed that it does not necessarily have to be replaced in the same element from which it was taken in order to make a tight joint.

In the accompanying drawing:

Figure 1 is a longitudinal sectional view through parts of a pair of fluid circulating tubes interconnected by an integral breeches piece closed at its outer end by a cleanout plug embodying the present invention;

Figure 2 is an end view corresponding to Fig. 1;

Figure 3 is a sectional view on the line 3—3 in Fig. 1;

Figure 4 is a sectional view on the line 4—4 in Fig. 1; and

Fig. 5 is an elevational view of one part of the cleanout plug.

The tubes 10 and 11, which may be considered to represent two parallel pipes of an economizer or the like, are serially interconnected at one end by an integrally formed breeches piece 12. Fixed to the open end of the breeches piece 12 by a weld joint 13 is a special tubular end piece 14 having an axial bore aligned with that of the breeches piece. The bore of end piece 14 is countersunk to provide an annular shoulder 15 against which a closure member 16 in the form of a circular disc may be seated to form a fluid-tight joint at the outer end of the return bend formed by the breeches piece. The end section 14 is of low carbon steel while the closure member 16 is made from a metal that is relatively harder and is formed on the portion thereof of registering with the annular seat 15 in the end piece with a plurality of sharp protuberances or serrations 17. This arrangement permits the serrations 17 to bite into the surface of the seating shoulder 15 when the closure member 16 is forced

endwise against it and provides an effective fluid tight seal.

It will be apparent that instead of providing a special end piece of softer metal than the closure member 16 the end portion of the breeches piece itself might be the softer element whether because the material of the tubes was originally softer or because of special treatment. Furthermore, with or without a separate end piece 14 5 the annular seat 15 of softer metal for the closure disc 16 might be provided in the form of a washer-like insert which would then be interposed between the shoulder 15 and the closure member 16.

10 The closure member 16 in the bore at the end of the breeches piece is mounted on a carrier 20. On its inner end face the carrier 20 has a recess 21 into which a reduced central neck portion 22 of the closure member 16 is loosely inserted so 15 that the closure member 16 may be moved relatively to the carrier 20 toward the seat 15 by a set screw 23 threadedly engaged in an opening extending axially of the carrier 20 from its outer end face to the base of the recess 21. While there 20 may be relative movement between the member 16 and its carrier 20 these parts are maintained 25 in their assembled relation by a circumferentially extending flange 25 at the outer end of the neck 22 on the closure member 16 adapted 30 to engage against an annular lip 26 at the inner end of the recess 21. Lip 26 is formed by peening over the metal of the carrier member adjacent a circumferential groove 27 (Fig. 5) at the inner end of the recess 21 of the carrier member.

35 The carrier 20 is retained in a predetermined axial position with respect to the seat 15 by diametrically located lugs 30 engaging in a recess about the bore in end piece 14, diametrical slots 32 (Fig. 2) extending from recess 31 to 40 the outer end face of end piece 14 providing a bayonet joint between the carrier and the end piece. Rotation of the carrier 20 with respect to the end piece 14 when in their assembled relation is prevented by a spring pressed locking pin 45 35 projecting from a pocket in the side wall of the carrier 20 near its outer end and engaging in a notch 36 formed at the outer end of the end piece 14.

When the carrier member 20 has been inserted 50 in the bore of end piece 14 and rotated to lock lugs 30 behind the shoulder parts of the recess 31 beyond slots 32 in the end piece 14, the set screw 23 may be turned to engage its inner end with the closure member 16 and force the latter against the seat 15 so that the hard metal

serrations 17 become imbedded in the seat 15 of softer metal and assure fluid tight contact between the end face of the closure member and the annular seat 15. When it is desired to clean either of the tubes 10 or 11 the set screw 23 may first be backed off somewhat to relieve the pressure between the lugs 30 on the carrier and the outer side wall of recess 31 in the end piece 14. The locking pin 35 is then depressed so that the carrier 20 may be rotated to aline the lugs 30 thereon with the slots 32 in the end piece to enable the carrier 20 and closure member 16 to be drawn axially out of the end piece 14.

Because of the construction described above, the closure member 16 remains attached to its carrier 20 thereby preventing loss of individual parts of the cleanout plug. Furthermore when several cleanout plugs have been removed any one of them may be inserted in the breeches piece from which another may have been dismounted inasmuch as the provision of the hard serrations 17 on the end face of the closure member bite into and establish a new seat for a closure member on the soft shoulder within any breeches piece into which the cleanout plug is inserted.

What I claim is:

1. A removable cleanout plug for a fluid circulating pipe having a bore countersunk to provide an annular shoulder; a closure carrier removably mounted in the enlarged or countersunk part of said bore; means for maintaining said carrier fixedly positioned in said bore outwardly of said shoulder; a closure member interposed between said carrier and said shoulder having an end face adapted to seat against the latter in overlying relation with respect to said bore; a plurality of protuberances on the end face of said member opposite said shoulder and formed of relatively harder material than the latter; and a set screw or the like projecting axially through said carrier to engage and force said closure member toward said shoulder for causing said relatively hard protuberances to bite into the soft surface of the latter.

2. A removable cleanout plug for a fluid circulating pipe having a bore countersunk to provide an annular shoulder; a closure carrier removably mounted in the enlarged or countersunk part of said bore; means for maintaining said carrier fixedly position in said bore outwardly of said shoulder; a closure member loosely mounted on said carrier member and projecting beyond the inner end thereof to seat against said shoulder and overlie said bore; a plurality of sharp protuberances on said closure member registering with said annular shoulder and formed of relatively harder material than the latter; and an adjustable set screw projecting axially through said carrier into engagement with said closure member for moving it axially on said carrier into engagement with said shoulder to cause the protuberances on said closure member to become imbedded in the soft metal of said shoulder.

3. A removable cleanout plug for a fluid circulating pipe comprising; an end piece of relatively soft metal attached to the pipe and formed with a bore alined with the pipe axis; an annular shoulder within said bore; a closure carrier removably mounted in said bore in outwardly spaced relation to said shoulder; a closure member interposed between said carrier and said shoulder and having an end face adapted to seat against the latter in overlying relation with respect to said bore; a plurality of protuberances located on the end face of said member opposite said shoulder and formed of relatively harder material than the latter; and a set screw or the like projecting axially through said carrier to engage and force said closure member toward said shoulder for causing said relatively hard protuberances to bite into the soft surface of the latter.
4. A removable cleanout plug for a fluid circulating pipe having a bore countersunk to provide an annular shoulder; a closure carrier removably mounted in the enlarged or countersunk part of said bore; means forming a bayonet joint between said end piece and carrier so arranged as to removably lock said carrier in said bore in outwardly spaced relation to said shoulder; a closure member loosely mounted on said carrier member and projecting beyond the inner end thereof to seat against said shoulder and overlie said bore; a plurality of sharp protuberances on said closure member registering with said annular shoulder and formed of relatively harder material than the latter; and an adjustable set screw projecting axially through said carrier into engagement with said closure member for moving it axially on said carrier into engagement with said shoulder to cause the protuberances on said closure member to become imbedded in the soft metal of said shoulder.

5. A removable cleanout plug for a fluid circulating pipe having a bore countersunk to provide an annular shoulder; a closure carrier positioned in said bore formed with a recess in its inner end face; means maintaining said carrier positioned in outwardly spaced relation with respect to said shoulder; a closure member interposed between said carrier and said shoulder having an end face adapted to seat against the latter in overlying relation with respect to said bore; a plurality of protuberances located on the end face of said member opposite said shoulder and formed of relatively harder material than the latter; a neck on the outer end of said closure extending into said recess in said carrier; cooperating shoulders on the neck of said closure member and the wall of said recess for loosely connecting them; and a set screw extending axially through said carrier into its recess for engaging said closure member to move it axially of said bore into engagement with said annular shoulder.
